[57] ABSTRACT

A speech-controlled bidirectional amplifier that includes first and second transmission channels each with a control member controlled by speech signals derived at control points preceding the control member. First and second comparison devices responsive to the levels of the speech signals control a third comparison device that in turn controls the attenuation level of the control members. The amplifier is arranged so that in the rest condition both control members provide a high signal attenuation. When speech signals are transmitted through one channel, the other channel is cut-off. However, an interrupt facility is provided whereby a speech signal above a given level in the cut-off channel will cause the apparatus to switch over so that the cut-off channel is opened and the previously open channel is then cut-off.

SPEECH-CONTROLLED BILATERAL AMPLIFIER

The present invention relates to a speech-controlled bilateral amplifier in which each amplifying channel includes a control member governed by a control circuit to which speech signals are applied that are taken from the two amplifying channels at points preceding the control member of each channel.

Such amplifiers may be employed with loud-speaking telephones or so-called intercom systems which allow a conversation in two directions. The inputs of the amplifiers are connected to microphones and the output to loud speakers, the microphone of one channel being located in the same room as the loudspeaker of the other channel and conversely. In general it is required to arrange the microphone and the loudspeaker in the same cabinet so that they are positioned relatively close together. A very strong acoustic coupling between the two elements is then unavoidable.

This implies the risk of acoustic feedback. In order to avoid same it is common practice to have the amplifier controlled by the speech signals so that the channel in use has a high amplification and the other channel is cut off or at least has a sufficiently low amplification.

Of course, this method of control has to be performed rapidly and smoothly and apart therefrom such systems have to satisfy various other requirements.

When one of the parties starts speaking the associated amplifying channel has to open rapidly, even for a low speech level, so that even the beginning of the first word will not be lost. During short intervals between words or sentences of the conversation it should not be possible for the direction of transmission of the amplifier to be automatically reversed due to reverberation or cross-talk between the loudspeaker and microphone in the other room.

It is desirable for the loudspeaker to reproduce the sound with adequate volume, for example, at the normal speech level, whereas at any instant the other party should be able to interrupt the first one and to reverse the direction of transmission of the amplifier without the need for raising his voice markedly. The reversal of the channels should be performed rapidly so that each party is able to make a remark during the continuous flow of words of the other party without the beginning of the remark being suppressed due to inertia of the interchange. In addition, the interchange of the channels should not give rise to instability.

It is particularly important that the persons speaking should be free to move about in the rooms so that they need not always be near the microphone-loudspeaker combination.

Known devices do not satisfy all of said requirements or satisfy them only to a limited extent because great difficulties arise from the fact that various requirements are to some extent in conflict with each other.

In general a loudspeaker is located nearer to the microphone than the person talking into it. When the loudspeaker reproduces the sound at speech level, the associated microphone which picks up the cross-talk signal can obviously provide a much stronger signal than the microphone to which the direct speech signal is applied.

In systems in which speech signals for controlling the amplification are derived in each channel at a point preceding the control members and in which the channel to which the stronger microphone signal is applied dominates and is driven to full amplification whereas the other channel is cut off, it is not possible, due to the strong cross-talk between the loudspeaker and the microphone, to obtain a high acoustic amplification, that is to say, a strong sound reproduction, and moreover the parties have to remain near the microphones.

In known devices in which the speech control signals are derived at a point beyond the control members, a strong sound reproduction can be obtained, but it is very difficult to interrupt the conversation except in the case of long pauses in the other party's speech.

The invention provides a particularly efficacious solution of these problems.

The invention is characterized in that the speech signals from each channel are applied each through a first signal circuit to a first input of two comparison devices and the speech signals from each channel are furthermore each supplied through a second signal circuit to a second input of the two comparison devices. The amplification of the first two signal circuits exceeds that of the second signal circuits and the comparison devices are designed so that they supply an output work signal when the signal level at the first input is higher than that at the second input. The output signals are fed to an input of a first and a second gate circuit, respectively, in a third comparison device, while the outputs of the gate circuits are coupled with a second input of the other gate circuit in a manner such that, when a work signal is fed to one of the first-mentioned inputs of one of the gate circuits the other gate circuit is cut off. The control voltages for the two control members are taken from the outputs of the gate circuits of the third comparison device.

The invention will be described more fully with reference to a single preferred embodiment shown schematically in the sole FIGURE of the accompanying drawing.

The amplifier comprises two channels. In one channel the speech signal of the microphone M_1 is applied through the microphone preamplifier T_1 , auxiliary control member DR_1 , the control member R_1 and the output amplifier U_1 to the loudspeaker H_1 . The other channel is arranged in an identical manner and comprises the preamplifier T_2 , auxiliary control member DR_2 , the control member R_2 and the output amplifier U_2 . The auxiliary control members DR_1 and DR_2 may be omitted since they are not essential to the invention. The purpose and function thereof will be described in detail below. The microphone M_1 and the loudspeaker H_2 are located in the same room, as are the microphone M_2 and the loudspeaker H_1 . The speech signals for the control circuit are derived in the channels at points P_1 and P_2 preceding the control members R_1 and R_2 , respectively, so that these signals are not affected by the random states of the control members R_1 and R_2 .

The signal at point P_1 is applied through a first signal circuit including an amplifier FK_1 , a rectifier DA_1 and a delay device S_1 to the input A_1 of a voltage comparison device K_1 . The signal at point P_2 is applied similarly through the amplifier FK_2 , the rectifier DA_2 and the delay device S_2 to the input A_2 of a second comparison device K_2 . Moreover, the signals at points P_1 and P_2 are each applied through a second signal circuit including the amplifier FR_2 and the rectifier DB_2 , and the amplifier FR_1 and the rectifier DB_1 , respectively, to a second input B_2 and B_1 , respectively, of the comparison devices K_2 and K_1 , respectively.

The comparison devices K_1 and K_2 are arranged in known manner so that they supply an output work signal, for example, a high output voltage, when the signal level at their first input A_1 and A_2 , respectively, exceeds by a given threshold value the level at the second inputs B_1 and B_2 , respectively. The outputs of the comparison devices K_1 and K_2 are connected to the inputs C_1 and C_2 of the gates ND_1 and ND_2 of a third comparison device. The outputs of the gates ND_1 and ND_2 are each connected to a second input D_2 and D_1 , respectively, of the other gate and are furthermore connected via the junction points P_3 and P_4 to the control members R_1 and R_2 of the amplifying channels.

The gate circuits ND_1 and ND_2 may be formed by Nand-circuits so that the output voltage is low only when the voltage at the two inputs is high. Thus, the voltage at the output is high when the voltage at just one of the inputs is low. The control members R_1 and R_2 are arranged so that when the voltage at the points P_3 and P_4 , respectively, is high, the control members are cut off or at least the amplification in the amplifying channels is so low that acoustic feedback cannot occur. In principle, the operation of the arrangement is of course not dependent upon a given polarity of the various signal voltages, neither individually nor in relationship, so that it will be obvious that the gates may be arranged differently and, if desired, voltages may be inverted by means of inverters, for example,

the control voltages applied to the control members R_1 and R_2 , provided that the arrangement as a whole continues performing the same function.

Apart from a given degree of frequency dependence, if any, the signal levels at the various inputs of the comparison devices K_1 and K_2 are proportional to the signals delivered by the corresponding microphones, independently of the state of the control members R_1 and R_2 .

In the rest position of the arrangement the microphones do not deliver a voltage and the signal levels at the inputs of the comparison devices K_1 and K_2 are low (zero level) so that the voltage of A_1 is not higher than that of B_1 and that of A_2 is not higher than that of B_2 . The voltages at the inputs C_1 and C_2 of the gates ND_1 and ND_2 will be low and the voltages at point P_3 and P_4 will be high. The control members R_1 and R_2 are then cut off.

When someone talks into the microphone M_1 the signal produced by the microphone is amplified by the amplifiers T_1 , FK_1 and FR_2 and rectified by the rectifiers DA_1 and DB_2 so that the signal level at the inputs A_1 and B_2 increases. In known manner, the delay device S_1 is designed so that the rise in the voltage level at A_1 is substantially not delayed. The voltage at the input C_2 remains low, but that at the input A_1 exceeds that at the input B_1 so that a high voltage appears at both inputs C_1 and D_1 of the gate ND_1 and the voltage at point P_3 becomes low. As a result, the amplifying channel between the microphone M_1 and the loudspeaker H_1 is opened through the control member R_1 .

The loudspeaker H_1 is located in the same room as the microphone M_2 and preferably is mounted in the same cabinet as the microphone so that the distance between these two elements is small. It is desirable for the sound signal delivered by the loudspeaker H_1 to be as high as possible, preferably at the normal speech level. Therefore, the microphone M_2 also receives a very strong sound signal which, owing to the nearness of the loudspeaker H_1 , may be many times stronger than the sound received by the microphone M_1 . In a practical case, as a result of the direct cross-talk between the loudspeaker H_1 and the microphone M_2 , the strength of the signal at point P_2 may be 10 times that of the signal at point P_1 . This cross-talk signal is amplified via the amplifiers T_2 , FR_1 and FK_2 and subsequent to rectification by the rectifiers DB_1 and DA_2 it is applied to the inputs B_1 and A_2 so that the signal level at these inputs rises. However, owing to the acoustic delay between the loudspeaker H_1 and the microphone M_2 the rise of the signal voltage at the inputs B_1 and A_2 will take place somewhat later than at the inputs A_1 and B_2 and, more particularly, not before the voltage at point P_3 has become low.

The ratio between the amplification by the amplifiers FK_1 and FK_2 on the one hand and that by the amplifiers FR_1 and FR_2 on the other hand is chosen so that it slightly exceeds the ratio between the signals appearing at the points P_1 and P_2 when the microphone M_1 is talked into. When the signal strength at point P_2 is 10 times that at point P_1 , the signal amplification by the amplifiers FK_1 and FK_2 may be 11 times that of the amplifiers FR_1 and FR_2 .

As a consequence the signal level at the input B_1 remains slightly lower than that at A_1 so that the low voltage at point P_3 is maintained.

On the other hand, since the amplification by the amplifier FK_2 is much larger than that by the amplifier FR_2 , the signal at the input A_2 will be much stronger (for example, more than 100 times in the present case) than the signal at point B_2 . However, as a result of the aforesaid acoustic delay the voltage at the input C_2 cannot rise to a high value before the voltage at the input D_2 of the gate ND_2 has assumed a low value. As a result, the gate ND_2 is closed and hence the signal at the input A_2 cannot have any effect or, in other terms, the amplifying channel between the microphone M_1 and the loudspeaker H_1 remains open and that between the microphone M_2 and the loudspeaker H_2 remains cut off.

During the short intervals between the words this situation must not vary, at least not as long as the other party at the

microphone M_2 does not want to interrupt. It should be noted that as a result of the acoustic delay the signal at point P_2 not only appears somewhat later than at point P_1 , but also disappears somewhat later. Owing to the effect of the delay device S_1 , which discharges comparatively slowly, the high signal level at the input A_1 is maintained for a short time after the signal at point P_1 has disappeared, i.e., for a time sufficient to insure that the signal at point P_2 also has decayed. The party in

the other room may interrupt the first one by supplying an adequate sound signal to the microphone M_2 . Owing to the combined effect of this sound signal and of the cross-talk signal from the loudspeaker H_1 , the signal level at the input B_1 can rise above that at the input A_1 . As a consequence the voltage at the input C_1 of the gate ND_1 drops so that a high voltage appears at point P_3 , resulting in the cut-off of the control member R_1 . The voltages at the two inputs of the gate ND_2 are now both high. The point P_4 then has a low voltage so that on the one hand the gate ND_1 is closed and on the other hand the control member R_2 opens the amplifying channel between the microphone M_2 and the loudspeaker H_2 . This change-over is performed very smoothly.

As stated above, the signal level at the input B_1 initially was slightly lower than the signal level at the input A_1 . It is desirable for this difference to be as small as possible. This means that the microphone M_2 requires only a little additional signal for causing the signal level at B_1 to exceed that of A_1 or, in other words, the speaker at the microphone M_2 need raise his voice only to a slight extent to gain access to the device by reversing the direction of transmission of the amplifier.

Cross-talk from the loudspeaker H_1 to the microphone M_2 is in general comparatively intimately dependent upon frequency. When conventional loudspeakers and microphones are employed, cross-talk will be strongest at frequencies appearing at the central region of the speech spectrum, for example, between 1,000 Hz and 1,500 Hz. The ratio between the amplifications of FK_1 and FR_1 can then be adjusted in the optimum case so that at frequencies at which cross-talk is a maximum the signal level at the input B_1 still is slightly lower than that at the input A_1 . At higher and lower frequencies the level difference may then be considerably greater, which means that at these frequencies a comparatively strong signal has to be supplied to the microphone M_2 in order to cause the level at input B_1 to exceed that at A_1 . This is not desirable because it is quite possible that frequencies at which maximum cross-talk occurs are only weakly represented in the speech spectrum of the speaker.

In order to mitigate this disadvantage frequency correction may be carried out in the amplifiers so that the transmission through the amplifier FK_1 exhibits the same frequency dependence as the transmission of the signal through the control member R_1 , the amplifier U_1 , the loudspeaker H_1 , the microphone M_2 , the amplifier T_2 and the amplifier FR_1 .

A correction may be carried out, for example, only in the amplifiers FR_1 and FR_2 so that the amplification of the high and low frequencies exceeds that of the medium frequencies. As an alternative, a correction may be carried out only in the amplifiers FK_1 and FK_2 so that the low and high frequencies are amplified to a lesser extend than the medium frequencies. Even a mixed correction in the four amplifiers is possible. By means of this frequency correction it may be achieved that despite cross-talk the speech level of the interrupting party at the microphone M_2 need exceed the level at the microphone by only a small amount, for example, by 5 db.

When the loudspeakers and the microphones are arranged in the same cabinets, the cross-talk level will be high. This is only an imaginary disadvantage. There is also an advantage in that direct cross-talk exceeds by far indirect cross-talk due to reflections from nearby objects or echos in the room. The overall cross-talk is therefore a practically constant factor and exhibits very little dependence upon the incidental disposition of the loudspeaker microphone combination in the room. This permits an optimum adjustment of the amplifiers FK_1 , FR_1 , etc.

As stated above, in principle, in the rest condition the control members R_1 and R_2 may be adjusted so that they either completely cut off the amplifying channel or so that a small steady amplification is left. It has been found that the latter alternative is to be preferred because in that case the distance between the rest condition and the completely open condition of the channel is smaller so that the opening of a channel from the rest condition is performed more smoothly or, in other words, even if the strength of the first syllable spoken is comparatively low, the relevant amplifying channel is immediately opened so that no part of this syllable is clipped.

However, some degree of transmission will then take place also through the channel not conveying speech which is not desirable in view of the fact that due to cross-talk the sound level at the microphone of said channel is much higher than at the microphone of the open channel. This may give rise to acoustic feedback in the system.

In order to avoid this phenomenon, auxiliary damping or control members DR_1 and DR_2 may be included in the amplifying channels. These auxiliary control members are controlled by the voltages at points P_4 and P_3 , that is to say by the control voltages which govern the control members in the other channel. The damping members DR_1 and DR_2 are arranged so that they are conducting in the rest condition of the arrangement, that is to say, in the example described above, when there is a high voltage at the points P_4 and P_3 . When speech is transmitted through the amplifying channel between the microphone M_1 and the loudspeaker H_1 , the voltage at point P_4 remains high so that the damping member DR_1 continues to conduct. However, under the control of the low voltage at point P_3 the damping member DR_2 completely cuts off the other amplifying channel.

What is claimed is:

1. A speech-controlled bidirectional amplifier comprising first and second amplifying channels each of which includes a transmission control member governed by a control voltage derived from the speech signals appearing in the two amplifying channels at control points preceding the control member of each channel, first and second comparison devices each having first and second inputs and designed so that they supply an output work signal when the signal level at the first input exceeds the signal level at the second input, means for applying the speech signals of each channel individually through a pair of first signal circuits to the first input of the two comparison devices and individually through a pair of second signal circuits to the second input of the two comparison devices, the amplification of the first two signal circuits being arranged to exceed that of the second two signal circuits, a third comparison device including first and second gate circuits each having first and second inputs, means for individually applying said output work signals to the first input of said first and second gate circuits respectively, means for coupling the output of each gate circuit with the second input of the other gate circuit in a manner such that a work signal applied to one of the first inputs of one of the gate circuits will cut off the other gate circuit, the control voltages for the two control members being derived from the outputs of the gate circuits of the third comparison member.

2. An amplifier as claimed in claim 1, characterized in that the first and/or second signal circuits include frequency-correction circuits arranged to produce a uniform frequency response over a wide range of audio frequencies.

3. An amplifier as claimed in claim 1 characterized in that the two first signal circuits each include a charging circuit for maintaining the signal voltages appearing at the first inputs of the first and second comparison members for a given time after the speech signal applied to the respective signal circuit has terminated.

4. An amplifier as claimed in claim 1, characterized in that

the control members are adjusted to a control level such that in the rest condition of the amplifier each channel is partially open and exhibits a relatively low amplification, each amplifying channel further including a second control member governed by the control voltage developed at the output of the gate circuit of the other channel so that when one channel is open in response to a speech signal the other channel is completely cut off.

5. A voice-operated bidirectional amplifier comprising first and second transmission channels including first and second transmission control members, respectively, each controlled by speech signals appearing at a control point in each channel that precedes the respective channel control member, first and second comparison devices each having first and second inputs and designed to compare the signal levels applied thereto so as to produce a first output signal when the signal level at the first input exceeds the signal level at the second input, a first pair of signal coupling circuits for individually coupling the speech signals at the control points of said first and second channels to the first input of said first and second comparison devices, respectively, a second pair of signal coupling circuits for individually coupling the speech signals at the control points of said first and second channels to the second input of said first and second comparison devices, respectively, a third comparison device including first and second gate circuits each having first and second inputs, means for coupling the output of said first and second comparison devices to the first input of said first and second gate circuits, respectively, means for coupling the output of the first gate circuit to the second input of the second gate circuit and to a control terminal of said first control member, and means for coupling the output of the second gate circuit to the second input of the first gate circuit and to a control terminal of said second control member, said first, second and third comparison devices being arranged so that in the rest condition of the amplifier with no speech signals present each gate circuit supplies a first control voltage to its respective control member that conditions same to provide high signal attenuation and simultaneously primes the second input of the other gate circuit so that the first channel to receive a speech signal will switch its respective gate circuit to provide a second control voltage that conditions its respective control member to provide low signal attenuation and simultaneously blocks the operation of the other gate circuit.

6. An amplifier as claimed in claim 5 wherein said first and second pairs of coupling circuits are arranged to transfer signals to the inputs of said first and second comparison devices that are proportional to the signal levels appearing at the respective channel control points so that the comparison devices can be switched in the middle of a speech transmission by an increase in the level of the signal coupled to the second input of the operative one of said first and second comparison devices such that the signal level at the second input thereof exceeds the signal level at the first input thereof.

7. An amplifier as claimed in claim 6 wherein said signal coupling circuits are adjusted so that the amplification of the first pair of signal coupling circuits exceeds the amplification of the second pair of signal coupling circuits.

8. An amplifier as claimed in claim 5 further comprising signal delay means connected in series with the first inputs of said first and second comparison devices.

9. An amplifier as claimed in claim 8 wherein said first and second pairs of coupling circuits are arranged to transfer signals to the inputs of said first and second comparison devices that are proportional to the signal levels appearing at the respective channel control points and independently of the attenuation condition of said first and second control members.
